UNITED STATES PATENT OFFICE

2,599,903

MOVABLE SIMULATED BOWLING PIN
SUPPORT AND LATCH THEREFORLyndon A. Durant and Melvin J. Binks, Chicago,
Ill., assignors to Republic Patent Corporation,
Chicago, Ill., a corporation of Illinois

Application April 22, 1950, Serial No. 157,552

1 Claim. (Cl. 177—329)

1

This invention relates to a movable simulated bowling pin support and latch therefor in which the bowling pin is supported in vertical position and when released is movable by a spring means from such position to a horizontal position. As such, the object of this invention is to provide a device of this character which will be simple in construction and economical in manufacture.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the bowling pin latch and supporting means;

Fig. 2 is a side elevational view of the same showing the same mounted upon a supporting panel; and

Fig. 3 is a sectional detail view showing the pin positioned in a horizontal position with respect to a supporting panel.

The several objects of this invention are accomplished by the preferred form of construction which comprises a rod 10 formed of substantially rigid material. Secured to one end of this rod as at 11 is a simulated bowling pin 12. Intermediate its opposite end portions the rod 10 is bent as at 13 to provide spaced parallelly extending sections 14 and 16. The section 14 is journaled in a bearing 15. The section 16 terminates into a return extension 17 of the rod 10. This return extension 17 provides a loop 18 to which is attached as at 19 one end of a spring 20. The opposite end portion of this spring 20 is connected as at 21 to a supporting panel 22. The bearing 15 is formed as an integral part of a mounting plate 23 secured as at 24 to the panel 22. This plate 23 has an upwardly extending portion 25 supporting an electromagnetic coil 26.

A plate 27 is connected to the portion 25 and extends parallel with respect to one side of the coil 26 to pivotally support an armature 28 with respect to the core 29 of the coil 26. This armature 28 is pivoted away from the coil by means of a spring 30. The armature 28 provides at its lower end portion a latch plate 31 adapted to have latched engagement with the section 16 provided by the rod 10.

The simulated bowling pin 12 is maintained in a vertical position as shown in Figs. 1 and 2 by reason of latched engagement between the section 16

2

and the latch bar 16. When the coil 26 is energized and the armature 28 attracted to the core thereof the latch plate 31 will move from latched engagement with respect to the section 16 thereby releasing the rod 10 for pivotal movement under the action of the spring 20. This pivotal movement of the rod 10 by the spring 20 will dispose the simulated pin in a horizontal plane beneath the supporting panel 22. To cushion the engagement between the pin 12 and the panel 22 a cushion pad 32 is provided. This cushion pad is carried by a plate 33 connected as at 34 to the panel 22.

A suitable mechanism may be provided for returning the pin to its vertical position. In this particular instance, we have provided a reset bar 35 slidably supported by a bracket 36 beneath the panel 22 and having a cross bar 37 which is adapted to engage the bent portion 13 of the rod 10. The arrangement is such that when the reset bar 35 is moved to the left as shown in Fig. 3 the cross bar 37 will engage the portion 13 and pivot the rod 10 clockwise as viewed in Fig. 3 to dispose the pin 12 in a vertical plane with the section 16 in latched position with respect to the latch plate 31. Any suitable means may be employed for moving this reset bar and any approved power circuit may be employed to energize the coil 26.

The invention may be employed in any type of bowling game and any number of simulated pins may be employed. It will be apparent that the mechanism for moving the pin to its vertical plane and for latching the same in such position is a simple and economical structure as is the arrangement for releasing the pin and for moving the same back to a horizontal position.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claim.

Having thus described our invention, what we claim as new and desire to protect by Letters Patent is:

A device of the class described comprising a substantially L-shaped mounting plate having one leg portion mounted on a fixed support, an electromagnetic coil including an armature mounted on the other leg of said plate, a latch plate provided by the armature, a bearing pro-

vided by said one leg, a rod member having one end portion bent to provide substantially parallelly extending spaced apart sections, one of said sections being journaled in said bearing, the other of said sections being adapted to have latched engagement with the latch plate while said electromagnetic coil is deenergized, a simulated bowling pin carried by the rod member at one end thereof, spring means connected to the opposite end portion of the rod member and to 10 said support for pivoting the rod member in a direction to dispose said other section from latched engagement with the latch plate, and means for pivotally moving said rod member in an opposite direction against the action of said 15

spring means to dispose said other section in latched engagement with the latch plate.
